UNITED STATES PATENT OFFICE.

ALVA L. KITSELMAN, OF RIDGEVILLE, INDIANA.

DESIGN FOR A WIRE FENCE.

SPECIFICATION forming part of Design No. 31,092, dated June 27, 1899.

Application filed July 30, 1897. Serial No. 646,562. Term of patent 7 years.

To all whom it may concern:

Be it known that I, ALVA L. KITSELMAN, a citizen of the United States, residing at Ridgeville, in the county of Randolph and State of Indiana, have invented a new and original Design for a Wire Fence, of which the following is a specification.

This invention relates to a new and original design for a wire fence; and it has for its object to provide a design of this character that shall be both useful and ornamental.

The leading feature of the design resides in a wire fence having a series of continuously and regularly waving longitudinal strands and interwoven cross or weft strands having twisted portions at their points of intersection with the waving longitudinal strands and forming the diagonal straight boundary-lines of rows of diamond-shaped meshes bisected in one direction by said waving longitudinal strands.

In the drawing the figure is a plan view or elevation of a section of wire fence or fencing embodying the herein-described design.

Referring to the drawing, the numeral 1 designates the longitudinal strands or warp-wires of the fence, which are formed with

long pitch-coils and extend longitudinally of the fence or fencing in parallel planes. The long coils of the strands or wires 1 impart thereto a continuous and regular wavy appearance, and thereby produce in elevation a series of regularly-curved symmetrical crimps or bands 2. The longitudinal strands or warp-wires 1 are intersected by the interwoven cross or weft strands 3, which have twisted portions 4 at their points of intersection with the strands or wires 1 and form the diagonal straight boundary-lines of rows of diamond-shaped meshes 5, which meshes are bisected by the wavy strands or wires 1, said wavy strands or wires of course only bisecting said meshes in one direction.

What I claim is—

The design for a wire fence, herein shown and described.

In testimony that I claim the foregoing as my own I have hereto affixed my signature in the presence of two witnesses.

ALVA L. KITSELMAN.

Witnesses:

C. M. KITSELMAN,
O. L. BARBER.
